UNITED STATES PATENT OFFICE

HANS DREYER, OF DUSSELDORF, GERMANY, ASSIGNOR TO SCHLOEMANN AKTIEN-
GESELLSCHAFT, OF DUSSELDORF, GERMANY

AIR BRAKE MECHANISM FOR PILGER MILL FEED GEARS

Application filed March 16, 1928, Serial No. 262,262, and in Germany March 18, 1927.

In feeding apparatus for pilger mills an important element is the braking and taking up of the shock due to the moving mass of the mechanism including a blank in the form of a pierced billet or a hollow bloom, a mandrel bar, coupling box, rod, etc., which mass is moved forwardly at a high velocity to bring the blank into the bite of a pair of swaging rolls. Liquid or air in combination with various mechanical means have been used for such braking. With liquid-operated brakes, the throttling, that is, the absorption of the stored-up energy, causes the liquid in time to become very hot, requiring the provision of special cooling means. In air-operated brakes, the rapid compression of the air causes it and the walls of its container to become highly heated. The compressed heated air is either allowed to escape to the atmosphere, or is returned through pipes to the compressed air cylinder which provides driving power for the forward movement of the reciprocating parts of the feeding mechanism. The brake compression, which gradually becomes hotter and the dimensions of which are fixed, causes the air flowing in it to immediately become heated and to accordingly expand and add additional pressure. Because of this heating, the specific gravity of the air becomes less and less, and the weight of the air to be compressed continues to decrease, so that the distance through which the brake acts also becomes shorter and shorter with the compression pressure greater than originally intended. Hence, irrespective of the air loss through the adjustment of the braking path, the quantities of air for the compression work must be continuously varied to correspond with varying temperatures.

The object of the invention is to provide a brake for a pilger mill feeding apparatus which is simple and effective in construction and which overcomes the prejudicial features incident to the use of the fluid brakes heretofore used.

The invention is illustrated in the accompanying drawing which is a vertical central longitudinal section through a pair of pilger

mill swaging rolls and feed apparatus associated with them.

According to this invention a suitable part of the reciprocating portion of a feed apparatus for a pilger mill is utilized as a brake piston rod and is surrounded by a brake cylinder adapted to contain a body of liquid. Above, and in free communication with this cylinder there is a closed reservoir, the lower portion of which and the cylinder are provided with a body of liquid. Air, or any other suitable gas, occupies the space above the liquid in the reservoir. The piston rod, which reciprocates through the liquid-containing cylinder, is provided with a piston so constructed and positioned that on the forward feeding stroke of the piston, the liquid, or a portion of it, in the cylinder, is driven into the reservoir against the compression resistance of the air in its upper portion which affords effective braking resistance to the forward movement of the moving mass. The heat developed consequent upon this compression of the air is absorbed by the upper portion of the liquid and the wall of the reservoir, and becomes dissipated on the rearward movement of the feed mechanism, during which movement the compressed air acts through the liquid and on the piston to urge the feed mechanism rearwardly.

Having reference now to the illustrative embodiment of the invention, there is shown a pair of swaging rolls 1 of familiar construction, the rolls being indicated as acting upon a blank 2 supported by a mandrel bar 3, suitably attached by a coupling box 4 to the end of a rod 5 forming part of the feed mechanism. While any suitable motive power may be used for moving rod 5 and its attached mandrel forwardly, this is preferably done by compressed air. To such end, the rear portion of rod 5 is connected to a tubular rod 6 of larger diameter than rod 5, rod 6 being provided with a piston 7 which operates in a compressed air cylinder 8. Rearwardly of piston 7, there is a twist nut 9 which receives a suitably threaded spindle 10 attached to the piston. For turning the twist nut through an angle of 90° at the proper time during each cycle of operation of the

swage rolls as is commonly done in pilger mills, the outer end of the nut is attached to a suitable turning mechanism 11 which may be of any desired type of construction.

5 Compressed air cylinder 8, and also the brake mechanism about to be described, are attached to a carrier 12 which is slidably mounted upon a suitable frame 13, the detailed construction of which together with 10 the mechanism for moving carrier 12 forwardly increment by increment being well known in this art, and accordingly not illustrated.

Surrounding rod 5 there is a cylinder 15 provided at its forward end with a packing gland 16 through which the rod reciprocates, and at its rear end with a similar gland 17 through which the forward end of tubular rod 6 reciprocates. By this construction the 20 enlargement formed at the point of connection of rod 5 and tube 6 forms a piston 18 in cylinder 15. Attached to cylinder 15, and projecting above it, there is a reservoir 19 in free communication with the cylinder. As 25 indicated on the drawing, cylinder 15 and the lower portion of reservoir 19 is provided with a body of liquid 20 which is preferably oil, the space 21 above the oil in the reservoir being filled with air. To vary the relative proportions 30 of air and liquid in the reservoir for the purpose presently to be explained, the reservoir is provided with a valve controlled air passage 22 and a valve controlled liquid passage 23.

35 In operation, the movable mass of the feed mechanism, including blank 2, mandrel 3, coupling box 4, rods 5 and 6, piston 7 and spindle 10, is moved rearwardly by the action of the swaging rolls 1 which rotate in the direction indicated by the arrows adjacent to them. This rearward movement is resisted by air in cylinder 8 in the rear of piston 7, which air becomes compressed. When the ends 25 of the enlarged portions of rolls 1 move from 40 engagement with blank 2 the compressed air in cylinder 8 at the rear of piston 7 exerts its pressure to thrust forwardly the movable parts of the feed mechanism just explained.

During this forward movement, piston 18 50 on rod 5 forces the liquid, or a portion of it, from cylinder 15 into reservoir 19 which results in compressing the air in the upper portion of the reservoir. Resistance to this compression of the air in the reservoir affords an effective brake resistance to the forward movement of the movable parts of the feed mechanism, which resistance may be varied to meet different requirements of service by 55 varying the relative amounts of air and liquid in the reservoir through valve controlled passages 22 and 23. On the rearward movement of the feed mechanism, the compressed air in the upper portion of reservoir 60 5 19 acts through the body of liquid 20 and

upon piston 18 to urge the mechanism rearward.

According to the provisions of the patent statutes, I have explained the principle of my invention, and have illustrated and described what I now consider to represent its best improvement. However, I desire to have it understood that, within the scope of the appended claims, the invention may be practiced by other forms of construction than 75 specifically illustrated and described.

I claim as my invention:

1. A feed apparatus for a pilger mill, comprising a cylinder, mandrel-carrying mechanism including a rod reciprocable through 80 and provided with a piston within said cylinder, and a closed reservoir above and having free liquid-flowing communication with said cylinder, said cylinder and the lower portion of the reservoir being provided with a body 85 of liquid which freely flows to and from the cylinder and reservoir during the entire reciprocation of said piston, and the upper portion of the reservoir containing air forming the sole brake for said mechanism. 90

2. A feed apparatus for a pilger mill, comprising a cylinder, mandrel-carrying mechanism including a rod reciprocable through 95 and provided with a piston within said cylinder, a closed reservoir above and having free liquid-flowing communication with said cylinder, said cylinder and the lower portion of the reservoir being provided with a body of liquid which freely flows to and from the cylinder and reservoir during the entire 100 reciprocation of said piston, and the upper portion of the reservoir containing air forming the sole brake for said mechanism, and means for varying the relative proportions of air and liquid in said reservoir to vary the 105 braking resistance.

In testimony whereof, I hereunto sign my name.

HANS DREYER.
